AUTOMATIC FEED AND VACUUM CONTROL-LING DEVICE

Albert O. Tadewald, La Crosse, Wis.

Application September 20, 1937, Serial No. 164,828

4 Claims. (Cl. 123—103)

This invention relates to a feed and vacuum controlling device of that type having as an element thereof, a diaphragm, and aims to provide in a manner as hereinafter set forth, a device operated by and dependent upon the intake manifold vacuum, which will produce any desired stabilization of the vacuum in the intake manifold for the purpose of automatically controlling by vacuum acceleration and deceleration the speed of internal combustion engines used in connection with automotive vehicles; also to eliminate the stalling of the windshield wiper due to drop in vacuum of intake manifold; to prevent a too rapid advance or retard on vacuum controlled distribution depending upon its design; and for improving the operation of all vacuum controlled or operated accessories attached to the intake manifold vacuum of an internal combustion engine.

The speed of the engine of an automotive vehicle is regulated by the butterfly valve in the carburetor. When the engine of the vehicle is running normally, there is a vacuum created in the intake manifold which sucks air in the carburetor and causes the gasoline to vaporize. If one presses his foot on the accelerator, it moves the butterfly valve in the carburetor so as to increase or decrease the speed of the engine. When the engine is running at a fairly normal speed, the air adjustment of the carburetor works perfectly. However, when the engine is operating at a fairly slow speed and one presses down on the foot throttle, it causes the butterfly valve to open abruptly. By reason of the slow speed of the engine, the vacuum in the intake manifold is so reduced that the windshield wiper stalls, the spark on vacuum controlled distributor advances or retards beyond its proper angle and the gasoline coming into the carburetor is improperly mixed which results in the stalling and sputtering of the engine, which is very objectionable. It is the aim of this invention to provide, in a manner as hereinafter set forth, a device for installation in relation to the carburetor, intake manifold and gasoline pump of the engine of an automotive vehicle for overcoming the objection aforesaid as well as providing a practical vacuum controlled manifold for acceleration and deceleration relative to the speed of the engine.

A further object of the invention is the elimination of dangerous gases due to proper combustion.

Further objects of the invention are to provide, in a manner as hereinafter set forth, a device for the purposes referred to which is simple in its

construction and arrangement, strong, durable, compact, thoroughly efficient in its use, readily set up, conveniently installed with respect to an internal combustion engine, and comparatively inexpensive to manufacture.

With the foregoing and other objects in view, the invention consists of the novel construction, combination and arrangement of parts as will be more specifically referred to and are as illustrated in the accompanying drawings wherein is shown an embodiment of the invention, but it is to be understood that changes (such as attaching directly to original throttle of carburetor), variations and modifications may be resorted to which fall within the scope of the invention as claimed.

In the drawings:

Figure 1 is a top plan view of the device installed with respect to the intake manifold of the engine.

Figure 2 is a fragmentary view, broken away, and partly in vertical section of the device installed with respect to the intake manifold and carburetor of the engine and with the butterfly or controlling valve of the carburetor illustrated in dotted lines in idle position.

Figure 3 is a fragmentary view in vertical section of a modified form.

Figure 4 is a view similar to Figure 2 of still another modified form in idle position.

Figure 5 is a section on line 5—5, Figure 4.

Figure 6 is a section on line 6—6, Figure 5.

Figure 7 is a fragmentary view in top plan of the modified form shown in Figure 4.

Figure 8 is a view similar to Figure 4 of still another modified form in idle position.

Figure 9 is a fragmentary view in side elevation of the modified form shown in Figure 8 and Figure 10 is a fragmentary view in longitudinal section illustrating details of the form shown in Figure 1.

With reference to Figures 1 and 2 the intake manifold of an internal combustion engine is indicated at 1 and a carburetor of the down draft type at 2. The device includes the diaphragm 35 to be hereinafter referred to. The controlling valve for the carburetor 2 is indicated at 3 and is of the butterfly type. The valve 3 when the diaphragm 35 is in the dotted line position indicated at X is disposed nearly horizontally as clearly shown in Figure 2. The upper end of the manifold 1 aligns with the lower end of the carburetor 2. The aligned ends of the manifold 1 and carburetor 2 are flanged at 4, 4^a respectively. The flange 4 is formed with a pair of diametrical-ly disposed, laterally extended apertured ears 5.

6. The flange 4^a is formed with a pair of diametrically disposed laterally extending ears 7, 8. The ear 7 is apertured. Interposed between the aligned ends of the manifold 1 and the carbureter 2 is a sealing gasket 9 which is also arranged between the ears and flanges aforesaid. The ears 5, 7 are connected together by the holdfast means 10. The ear 8 is formed with a vertically disposed opening 11. Carbureter 2 at its lower end is formed with a radially disposed channel 12 which extends from the interior thereof to the opening 11. Mounted on the ear 8 and registering with the wall of opening 11 is a sealing gasket 13. Positioned on the gasket 13 is a vertically disposed sleeve 14 formed intermediate its ends with a laterally extended tubular extension 15 provided with internal and external threads. Positioned on the top of the sleeve 14 and registering with the inner face 20 of the latter is a sealing gasket 16. The inner face of the gasket 13, sleeve 14 and gasket 16 form flush continuations of the wall of the opening 11. Extending through gasket 16, sleeve 14, gasket 13 and opening 11 and threadedly engaging in the ear 6 is a headed clamping bolt 17 functioning to bind the gasket 16, sleeve 14, gasket 13 and ears 8, 6 together. The head of the bolt 17 seats upon gasket 16. The diameter of the bolt 17 is materially less than the inner diameter of the sleeve 14. The channel 12, opening 11, gasket 13 and sleeve 14 provide a suction conduit. Adjustably engaging with the inner face of extension 15, is a flanged tubular nipple 18 of greater length than extension 15. The channel 12 constitutes an outlet for the suction conduit. The nipple 18 constitutes an intake for the vacuum conduit and also functions as a calibrating means for a vacuum controlling spring to be referred to.

40 The valve 3 is fixed to its shaft 19 and is disposed diametrically of the carbureter 2. One side of the latter is formed with a bearing 20 through which extends shaft 19. The latter is also journaled in the body of the carbureter 2. Fixed to the shaft 19 and abutting the outer end of the bearing 20 is the tubular body part or hub 21 of a bell crank lever 22. The latter includes a horizontally disposed arm 23 and a vertically disposed arm 24 arranged at right angles to the inner end of the arm 23. The inner end of the arm 23 and the upper end of the arm 24 do not align, but are formed integral with the hub 21. The arm 23 is disposed at right angles to arm 24. The arm 24 depends from the hub 21. The outer end of arm 23 is forked as at 25. The lower end of arm 24 is forked as at 26.

60 Pivots connected to the forked end 25 of arm 23 is a vertically disposed actuator 27 of rod-like form pivotally connected to and for actuating a bell crank lever 28 employed for operating a fuel feed pump 29 of any suitable construction and which may be of the form as disclosed in Letters Patent 1,166,230 to Lemp, December 28, 1915. The bell crank 28 includes a horizontal arm 29^a and a vertical arm 29^b which normally depends from the pivot 29^c of the bell crank 28. The actuator 27 is pivotally connected to the outer end of arm 28. The lower end of the arm 29^b is connected with the pump structure 29 as at 29^d.

70 The device includes a diaphragm housing indicated at 30 and which is formed of a pair of oppositely disposed sections 31, 32. The section 31 axially thereof is formed with an opening 31^a and with a laterally disposed tubular internally

threaded extension 33 which encompasses and threadedly engages with the extension 15 on the sleeve 14. The housing sections 31, 32 are flanged as at 34 and with such flanges disposed in alignment. Arranged between the flanges 34 of the housing sections 31, 32 and within the housing 30 is a diaphragm 35 which divides housing 30 into a pair of compartments indicated at 36, 36^a. The opening 31^a forms an outlet for compartment 36. The flanges 34 and the diaphragm 35 are connected together by the holdfast means 37. The section 32 of housing 30 axially thereof is formed with an opening 38. Positioned against the central portions of the faces of the diaphragm 35 are oppositely disposed washers 39, 40 having their perimeters curved. Arranged against washer 39 and of less diameter than the diameter of the latter is a cup-shaped member 41. Positioned against the washer 40 and extending outwardly through the opening 38 from compartment 36^a is a coupling bar 42 rabbeted at its outer end as at 43. The diaphragm 36, washers 39, 40, member 41 and coupling bar 42 are clamped together by a headed screw 44 which extends axially through member 41, washer 39, diaphragm 36, washer 40 and has threaded engagement with the inner end of the bar 42. The head of the screw 44 is arranged within and seats against the member 41. Bearing against the nipple 18, extending into and bearing against member 41, as well as surrounding the head of the screw 44 is a calibrated vacuum controlling spring 45 normally acting to maintain the diaphragm 35 in the position shown in dotted lines Figure 2 which would be equal to 2 to 3 inches of vacuum. The adjustability of the nipple 18 provides for calibrating the spring 45.

Fixed to the section 32 of the housing 30 is a horizontally disposed outwardly directed support 46 to which is pivotally connected, as at 47 one end of a lever arm 48 which extends across and is pivotal at 49 upon the rabbeted outer end of bar 42. The other end of lever 48 is pivoted as at 50 to a combined pull and push rod 51 for the shaft 19. The rod 51 has its other end pivotally connected, as at 52 to the forked end 26 of the arm 24 of bell crank lever 22. The rod 51 has fixed thereon, intermediate its ends, a stop collar 53. Slidably keyed upon the rod 51 is a shiftable sleeve 55. The movement of the sleeve 55 in one direction is limited by the collar 53 and the latter also provides an abutment engaged by the sleeve when the latter is shifted for the purpose to impart a pulling action to rod 51. Connected at one end, as at 56 to the sleeve 55 is a foot controlled accelerating rod 57.

When the rod 57 has moved in the direction of the arrow 57^a to cause sleeve 55 to leave collar 53, the rod 51 will be moved in a like direction carrying lever arm 24 therewith and rocking shaft 19 to open valve 3. When pressure is relieved upon rod 57 it will move in an opposite direction to abut collar 53. As is well known, foot operated accelerating rods are spring controlled and in view of which when such rod is relieved of pressure it will automatically return to its normal position. When shaft 19 is rocked by rod 51, lever 22 will be moved in a direction to provide for the lowering of the actuator 27 whereby bell crank 28 will provide for the operation of the pump structure 29.

The suction in the intake manifold, when rod 57 is moved in direction 57^a will be such as to pull the diaphragm in a direction to compress

spring 45 and to provide a pushing action for rod 51 which tends to open the valve 3 and this action is continued until the vacuum drops below calibrated spring 45.

5 When the driver steps with great force on the foot operated accelerator of which the rod 57 forms a part, sleeve 55 leaves collar 53 and gives rod 51 free action to open valve 3 to an angle that is determined by the vacuum in the intake manifold. When the motor is at high speed the vacuum is high and therefore opens valve 3 completely providing rod 57 has moved sleeve 55 back far enough to allow collar 53, which is on rod 51, to open valve 3. The only time sleeve 55 10 abuts the collar 53 is when the motor is idling, at slow speeds or when the vacuum in the intake manifold is above 2 or 3 inches of vacuum.

X—indicates position of diaphragm in idle position with valve 3.

Y—indicates valve position when diaphragm is in position as indicated in Figure 2.

By this action one has a combined vacuum and spark timing control which at low speeds and heavy loads on an engine would maintain a certain minimum manifold vacuum of the order of two or three inches of mercury and at the same time permit the vacuum spark control to be set ahead of what it would be at wide open throttle and no manifold vacuum; also under these conditions to use a leaner fuel air ratio and prevent the stalling and sputtering of the engine.

With reference to the modified form shown in Figure 3, a sleeve indicated at 58 is for the same purpose as the sleeve 14. Sleeve 58 is not formed with an integral lateral tubular extension in the manner as sleeve 14, but in lieu thereof sleeve 58 intermediate its ends is formed with a threaded opening 59 with which an extension 60 which is to be an integral part of the section 31 of housing 30. The extension 60 is to be substituted for the extension 33 and is formed of two different inner diameters, the junction of which provides the shoulder 61. The portion of reduced inner diameter of the extension 60 is threaded and has engaging therewith a tubular nipple 62 which is for the same purpose as the nipple 18. The flanged end 63 of the nipple 62 is for abutting shoulder 61. The construction shown in Figure 3 illustrates parts which may be substituted for the sleeve 14, extension 15, extension 33 and nipple 18.

With reference to Figures 4, 5, 6 and 7, the carburetor with which a device in accordance with this invention may be employed is indicated at 64 and formed with a pair of diametrically disposed openings 65, 66 and laterally extending collars 67, 68 which have their inner faces register with the inner faces of the walls of openings 65, 66. Journaled in openings 65, 66 and collars 67, 68 is a tubular shaft 69 which extends outwardly from the collar 67. Fixed on that end of shaft 69 which projects from the collar 67 is a collar 70 having an outwardly directed arm 71 of arcuate cross section. Extending through and projecting from each end of the shaft 69 is a shaft 72 carrying a retaining means 73 at one end which abuts the collar 68. The shaft 72 has fixed thereon a sleeve 74 formed at its inner end with a rabbet 75 of arcuate contour. The outer diameter of sleeve 74 corresponds to the outer diameter of collar 70. The shaft 72 has secured therewith a retaining means 76 which abuts the sleeve 74. The length of the rabbet 75 is greater than the cross sectional length of the arm 71 whereby shaft 69 can be shifted, independently of the

shaft 72 in a manner to be referred to. Fixed to the shaft 69 is the controlling valve 77 for the carburetor 64 the valve being of the butterfly type and also acting to control the vacuum. When in inactive position or idle, the valve 77 is vertically disposed and when in active position it is arranged at an angle to the perpendicular by a means to be referred to.

The intake manifold of the engine is indicated at 78 and has its upper end aligned with the lower end of the carburetor 64. The lower end of the latter is formed with a flange 79 provided with a pair of lateral ears 80, 81. The ear 80 is apertured. The upper end of the intake manifold 78 is flanged as at 82 and with the latter formed with a pair of laterally disposed ears 83, 84. The ears 80, 83 are secured together by a holdfast means 85. The ear 81 is formed with a vertical opening 86. The lower end of the carburetor 64 is provided with a channel 87 which extends from 10 the interior of the carburetor to the opening 86. Interposed between the aligned ends of the carburetor 64 and intake manifold 78 is a sealing gasket 88. Positioned on the top of ear 81 is a sealing gasket 89. Arranged on the gasket 89 is a sleeve 90 formed intermediate its ends with an interiorly threaded tubular extension 91. Positioned on the sleeve 90 is a sealing gasket 92. Extending through the gasket 92, sleeve 90, gasket 89 and opening 86 is a bolt 93 formed at its lower 15 end with a threaded portion 94 which threaded portion engages in a screw threaded socket formed in the ear 84. The bolt 93 has a threaded upper portion 95 which is engaged by a clamping nut 96 of the cap type. The bolt 93 and nut 96 function to clamp gasket 92 and sleeve 90, gasket 91 and ears 81, 84 together. The opening 86, channel 87, gasket 89 and sleeve 90 form a suction conduit communicating with an opening 97 formed in the body of the sleeve 90. The extension 91 forms a continuation of the opening 87.

The device includes a diaphragm housing 98 formed of a pair of oppositely disposed laterally flanged sections 99, 100. Anchored between the flanges of the sections 99, 100 and extending across the housing is a diaphragm 101 which divides the housing into a pair of compartments 102, 103. The section 99 of housing 98 is provided axially thereof with an opening 104 and said section 99 on its inner face is provided with a boss 105 bordering the opening 104. Formed integral with the outer face of section 99 and registering with opening 104 is a tubular extension 106 having its inner face upon two different diameters to provide an internal shoulder. The portion of largest inner diameter is indicated at 107, the portion of smallest inner diameter at 108 and the shoulder at 109. The outer end of the extension 106 is reduced as at 110. The portion of smallest inner diameter 106 is threaded. The reduced portion 110 of extension 106 is threaded. The said reduced portion 110 threadedly engages with the inner face of the extension 91 to provide for connecting extension 106 with the sleeve 90. Threadedly engaging with the portion of smallest inner diameter of the extension 106 is a peripherally threaded flanged tubular nipple 111 having its flange normally abutting the shoulder 109. The nipple 111 functions for the same purpose 70 as the nipples 18 and 63.

Arranged against the opposite faces of the diaphragm 101 at the central portion of such faces are oppositely disposed washers 112, 113 having their perimeters curved. The section 100 of the

housing 98 has an axial opening 114 through which extends a coupling bar 115 of the same form as the bar 42 and functioning for the same purpose as bar 42. Positioned against the washer 112 is a washer 116 of materially reduced size with respect to that of washer 112. Extended through the diaphragm 101 axially thereof as well as through the washers 112, 113, 116 and anchored in the inner end to the coupling bar 115 is a headed screw 117 for clamping the washer 116, washer 112, diaphragm 101, washer 113 and bar 115 together. Arranged in the extension 106 and abutting against the flanged end of the nipple 111 and also abutting against washer 116 is a calibrated spring 118 for controlling the vacuum. The idle position of the device is as shown in Figure 4 with the spring 118 expanded and shifting the diaphragm 101 in one direction to provide for washer 113 closing the inner end of opening 114.

The sleeve 74 is provided with a crank arm 119 having a forked outer end 120. The arm 119 extends upwardly from the collar 70 and is normally disposed at an outward inclination from its lower to its upper end. Collar 70 has formed therewith a depending crank arm 121 having its lower end forked as at 122. The arm 121 inclines in an opposite direction from its upper end than the inclination of the arm 119 from the lower end of the latter. The upper end of the arm 119 is pivotally connected as at 123 to the rod 124 of an accelerator mechanism. The sleeve 74 has a lateral extending crank arm 125 which at its outer end is pivotally connected as at 126 to an actuator 127 for the fuel pump.

Extending rearwardly from the section 100 of housing 98 is a support 128 to which is pivotally connected as at 129 one end of a lever member 130. The latter is mounted intermediate its ends upon the rabbeted outer end 131 of the coupling bar 115. The pivot for the member 130 is indicated at 132 and is fixed to and extends above the lower wall of the rabbet on the outer end of the bar 115. The other end of the lever member 130 is pivotally connected as at 133 to the rear end of a rod or bar 134 for the shaft 69. The other end of the rod or bar 134 is pivotally connected as at 135 to the lower end of the crank arm 121.

The spring 118 functions for the same purpose as the spring 45.

Operation of the form shown by Figure 4:

The diaphragm is in its idle position (motor not running). When the motor is started the vacuum of the intake manifold is present on diaphragm 101 but produces no results because rod 124 which is connected to foot feed and crank arm 119 holds back arm 121 by its rabbet and thereby prevents lever 130 and 134 from opening throttle 77. When the foot feed pushes rod 124 in the direction of arrow 124a the crank arm 119 follows in the same direction which has a tendency to leave the rabbet on arm 121 but the vacuum action on diaphragm 101 pulls lever 130 which in turn pulls 134 in the direction of arrow 134a and that operates arm 121 which is connected to throttle 77. Now when the driver steps on the accelerator with force, arm 124 and crank arm 119 opens completely and arm 121 follows 70 until the vacuum or the diaphragm 101 reaches 3 inches of vacuum and that determines the angle of throttle 77 as the motor gains speed the throttle will open in proportion to its torque.

By this action one has a combined vacuum and spark timing control which at low speeds and

heavy loads on an engine will maintain a certain minimum manifold vacuum of the order of two or three inches of mercury and at the same time, permit the vacuum spark control to be set ahead of what it would be at wide open throttle and no manifold vacuum. Also, under these conditions, to use a leaner fuel/air ratio and prevent the stalling and sputtering of the engine and receive greater mileage on fuel.

With reference to Figures 8 and 9, a down draft carburetor is indicated at 136, its butterfly valve at 137 and the operating means for the latter at 138. The intake manifold of the engine is indicated at 139 and which endwise aligns with carburetor 136. The opposite ends of carburetor 136 and manifold 139 are flanged as at 140, 141 respectively, and interposed between such ends is a plate 142 formed with an opening 143 having its wall aligning with the inner faces of said flanged ends. The edges of the flanges 140, 141 and plate 142 are flush. The plate 142 is formed with a channel 144 which leads from the opening 143 and terminates in a threaded socket 145 opening at the edge thereof. The plate 142 is formed with an opening 146 which intersects the channel 144. The flanges 140, 141 and plate 142 are anchored together by the holdfast means 147. One of the means 147 extends through the opening 146. Arranged in the opening 143 of the plate 142 is a butterfly valve 148 carried by a shaft 149 journaled in and extended from plate 142. Connected to shaft 149 exteriorly of plate 142 is a crank arm 150. A diaphragm structure of the same form as that shown in Figure 4 is indicated at 151 and which has its tubular extension 152 extend into and is anchored to the wall of the socket. Extending from, connected to and shifted by the diaphragm of structure 151 is a movable part 153 which corresponds to part 115 of Figure 4, but it is not rabbeted. The part 153 includes a horizontal leg 154 and a vertical leg 155. The leg 154 slidably extends into the housing and is fixed to the diaphragm of structure 151. The leg 155 is pivotally connected at its upper end, as at 156 to a rod 157 which is common to crank arm 150 and leg 155. The rod 157 is pivotally connected to crank arm 150 as at 158.

When the motor is started the vacuum from the intake manifold pulls the diaphragm of the diaphragm structure in a direction to close the inner end of the tubular extension. As the diaphragm moves towards the tubular extension the part 153 is carried therewith whereby the rod 157 moves in a direction towards the carburetor and which in turn will open the butterfly valve 148 and permits the carburetor being free to operate as normal. When the driver steps on the foot operated accelerating mechanism with a great deal of force, the butterfly valve which is above the valve 148 opens completely and the intake manifold vacuum drops rapidly, but cannot go below the vacuum at which the calibrated spring within the diaphragm structure is set. It will be assumed that the calibrated spring has been set to close the valve 148 to six inches of vacuum. Now when the driver steps on the foot accelerating mechanism with force, the rod 157 partly closes the valve 148 and keeps the intake manifold at six inches of vacuum.

What I claim is:

1. In an automatic feed and vacuum controlling device for internal combustion engines, a structure providing a fuel conducting passage leading from a carburetor to the intake manifold

of the engine, a rotatable unit journaled in said structure and including a vacuum controlling valve arranged in said passage, said structure including a vacuum conduit opening at one end 5 into said passage between said valve and said intake manifold, a housing including a tubular extension connected to said structure and opening into the other end of said conduit, a spring controlled vacuum operated diaphragm arranged 10 in said housing, the controlling spring for said diaphragm being arranged within, and projecting from said extension into said housing against the diaphragm, said structure including an adjustable intake nipple for said conduit bearing 15 against and providing for calibrating said spring, and an oppositely movable shiftable means for rotating said unit in opposite directions operated from and connected to said diaphragm, extended outwardly from said housing and connected to 20 said unit.

2. In an automatic feed and vacuum controlling device for internal combustion engines, a structure providing a fuel conducting passage leading from a carburetor to the intake manifold 25 of the engine, a rotatable unit journaled in said structure and including a vacuum controlling valve arranged in said passage, said structure including a vacuum conduit opening at one end into said passage between said valve and said 30 intake manifold, a housing including a tubular extension connected to said structure and opening into the other end of said conduit, a spring controlled vacuum operated diaphragm arranged in said housing, the controlling spring for said diaphragm being arranged within and projecting from said extension into said housing against the diaphragm, said structure including an adjustable intake nipple for said conduit bearing against and providing for calibrating said spring, an oppositely movable shiftable means for rotating said unit in opposite directions operated from and connected to said diaphragm, extended outwardly from said housing and connected to said unit, the said shiftable means being provided with an 40 abutment, and means slidably mounted on said shiftable means and coacting with said abutment for bodily moving said shiftable means in one direction to rotate said unit independent of said diaphragm.

3. In an automatic feed and vacuum controlling device for internal combustion engines, a structure providing a fuel conducting passage leading from a carburetor to the intake manifold of the engine, a rotatable feed and vacuum control unit journaled in said structure including a vacuum controlling valve arranged in said passage, a fuel feed control exteriorly of said passage for a fuel accelerating pump and a pair of spaced 50 crank arms exteriorly of said passage bodily moving in unison and one constituting a rotator for the unit and the other an actuator for the actuating means, said structure including means providing a vacuum conduit opening at its outlet end 55 into said passage between said valve and said manifold, a housing including a tubular extension connected to said structure and opening into said conduit at the intake end thereof, a spring controlled vacuum shifted diaphragm arranged within the housing adjacent said extension, the controlling spring for the diaphragm being arranged within and projecting from said extension into the housing against the diaphragm, said means including an adjustable intake nipple for said conduit bearing against and providing for calibrating said spring, and a shifting means for bodily rotating said unit and shifted in opposite directions from and connected to said diaphragm, extended outwardly from said housing and connected to that arm constituting a rotor for said unit, the said shiftable means being provided with an abutment, and means slidably mounted on said shiftable means and coacting with said abutment for bodily moving said shiftable means in one direction to rotate said unit independent of said diaphragm.

ALBERT O. TADEWALD.
